UNITED STATES PATENT OFFICE.

FREDERICK F. BRAND, OF PITTSFIELD, MASSACHUSETTS, ASSIGNOR TO GENERAL ELECTRIC COMPANY, A CORPORATION OF NEW YORK.

TRANSFORMER.

Application filed June 3, 1925. Serial No. 34,694.

My invention relates to transformers and more particularly to that form of transformer in which the magnetic core has a winding leg surrounded by two concentric 5 cylindrical stacks of coils. The invention is an extension of the general principles disclosed in my United States Patent No. 1,536,761, issued May 5, 1925, and its general 10 object is to provide an improved arrangement for supporting the windings or coils and for maintaining them in proper relative positions and under proper compression during operation of the transformer.

A stack of high voltage windings or coils 15 must have a considerable amount of insulation on the conductor and this insulation or an appreciable part of it is commonly composed of material such as taping which is compressible so that the stack may shrink 20 while in service under the constant pressure of its supports. In some transformers having two concentric stacks of coils, both coils 25 are of this character but the shrinkage of the two stacks may be unequal. It is desirable or necessary that the stacks be kept tightly compressed to prevent distortion and displacement of the stacks and their component coils by the magnetic forces caused by the currents in the coils, particularly 30 under heavy overload or short-circuit conditions. One of the objects of my invention is to support the core of the transformer upon the two coil stacks by an arrangement which 35 will distribute the weight of the core upon the two stacks in a predetermined ratio and permit the two stacks to shrink, either equally or unequally, without disturbing the degree of compression to which they are subjected by the core.

40 If the magnetic centers of the two concentric cylindrical windings are displaced along the winding leg of the core, there exists a force which tends to increase this displacement. This displacing force may be very 45 great under abnormally heavy load or short circuit conditions if the displacement of the magnetic centers of the windings is a substantial one. There is no such displacing force, however, if the magnetic centers of

the windings coincide in position along the 50 winding leg of the core. A further object of the invention, therefore, is to provide improved winding supports arranged to permit shrinkage of the two windings, whether such shrinkage is equal or unequal and at the 55 same time to maintain the windings under compression and their magnetic centers coincident in position along the winding leg of the core. In attaining this result, it may be necessary to compensate for shrinkage of 60 only one of the windings if the other winding is for low voltage operation and has insulation which is not appreciably compressible because of the small quantity used or because of its incompressible character.

65 The invention will be better understood from the following description taken in connection with the accompanying drawings in which Fig. 1 is a view in elevation of a transformer constructed in accordance with 70 the invention, parts being broken away to reveal details. Figs. 2, 3, 4, and 5 are similar views in elevation of transformers constructed in accordance with different modifications of the invention, and Figs. 6 and 7 75 are elevation and plan views, respectively, of the transformer shown in Fig. 4.

80 Like reference characters indicate similar parts in the different figures of the drawings.

The particular transformer shown in Fig. 1 includes a core having a winding leg 10 surrounded by two concentric cylindrical stacks of windings or coils 11 and 12. The outer stack of coils 12 is for operation at 85 high voltage and a considerable proportion of the volume of the stack must therefore be insulation so that the stack may shrink and decrease in length appreciably after the transformer is placed in service and subjected to constant heavy compression between its end supports. The inner stack of coils 11, however, is for low voltage operation and only a small quantity of insulation is therefore necessary, the incompressible metal conductor composing most of the volume of this stack. After being assembled and placed in service, this low voltage stack of

coils 11 will therefore not shrink appreciably but its length will remain substantially constant throughout its life. The high voltage stack of coils 12 is mounted on a fixed supporting ring 13 carried on posts 14 above a base 15. The core is supported by brackets 16 secured to its upper end, the outer ends of the brackets 16 resting on the high voltage stack of coils 12. The stack of coils 12 is therefore compressed by the weight of the core 10 and the core is free to move downwardly by gravity to compensate for any shrinkage of this stack of coils. The incompressible low voltage stack of coils 11 is supported between the centers of a set of levers 17 at the upper end of the stack and the centers of a similar set of levers 18 at the lower end of the stack. The levers 17 and 18 have their inner ends pivoted to the movable core 10 and their outer ends pivotally supported by a plurality of adjustable sleeves 19 carried on supporting rods 20 fixed to the base 15. By adjusting the positions of the sleeves 19 on the rods 20, the pressure on the stack of coils 11 may be adjusted and the magnetic centers of the two stacks of coils 11 and 12 may be made to coincide in position along the winding leg 10 of the core. Top and bottom guides 21 secured to the core have slidable engagement with the supporting rods 19 to guide the core. The lower guides 21 carry sleeves 22 with tapered openings containing sets of balls surrounding the rods 19, the balls permitting the core to settle down with any shrinkage of the coil stack 12 but preventing any upward movement of the core or expansion of the coil stack 12. Inasmuch as the high voltage stack of coils 12 contains an appreciable amount of compressible insulation and is held in place under considerable pressure due to the weight of the transformer core, it may shrink and become shorter after the transformer is placed in service. Assuming that this stack of coils 12 is of uniform construction throughout its length, the magnetic center of the stack is midway between its two ends and any shrinkage will be distributed uniformly through the stack. From this and the fact that the lower end of the stack is immovably supported, it will be seen that any shrinkage of the stack will result in a settling or displacement of its magnetic center equal to one half that of its upper end and of the core. In order that the magnetic centers of the two coil stacks 11 and 12 may be maintained always coincident in position along the winding leg 10 of the core, it is therefore desirable that the inner incompressible low voltage stack 11 be moved or displaced a distance equal to one half the displacement of the core. This result is attained by the construction which has been described because any shrinkage and shortening of the high voltage winding

is accompanied by a corresponding displacement of the core and the inner ends of the levers 17 and 18 and by a displacement of the low voltage winding 11 and the centers of the levers 17 and 18 equal to one half 70 that of the core.

The form of the invention shown in Fig. 2 is applicable and useful in connection with the support of two concentric stacks of coils which are so constructed that there will be 75 about the same amount of shrinkage in the two stacks of coils or where the difference in the shrinkage of the two stacks will not be great enough to cause an objectionable displacement of their magnetic centers along 80 the winding leg of the transformer. The necessity for maintaining the coil stacks under tight and unyielding compression is largely to prevent motion of the stacks under load, especially under conditions of 85 heavy overload or short circuit. The magnetic forces in a winding are generally greater in the case of a low voltage winding than in that of a high voltage winding because 90 the current is greatest in the low voltage winding and it is the ampere turns in a winding which determine the magnetic flux causing such forces. A winding having a large amount of insulation is usually a high 95 voltage winding and the current which it carries, even under short circuit conditions, is not very great so that the resulting magnetic forces are also not very great. For 100 this reason, it is sufficient in some cases if the windings be kept tightly compressed and it is not always necessary to maintain the magnetic centers of two concentric windings coincident along the winding leg of the core. The two concentric stacks of coils 11 and 12 shown in Fig. 2 are mounted on fixed 105 supports 23 secured to the base 15. These coil stacks 11 and 12 surround the winding leg 10 of the magnetic core provided with brackets 24 secured to its upper end. The outer ends of the brackets 24 are pivoted to the centers of levers 25, the inner ends of the levers 25 resting on the inner coil stack 11 and the outer ends of the levers 25 resting on the outer coil stack 12. The core is thus supported by the two coil 110 stacks and its weight distributed upon them by the levers 25 to keep them tightly compressed while in service. As the stacks shrink, the core settles to compensate for the shrinkage and the levers 25 tilt one way or the other to compensate for any inequality in the shrinkage of the two stacks, the pressure on each stack due to the weight of the core remaining unchanged. Any inequality 115 in the shrinkage of the two will of course be accompanied by a displacement of their magnetic centers along the winding leg 10 of the core. This displacement of the magnetic center of the two stacks will be 120 only one half as great as the difference in 125 130

shrinkage and will be within allowable limits for the reasons which have been explained.

In the form of the invention shown in Fig. 3, the supporting means for the coil stacks 11 and 12 will permit the two coil stacks to shrink unequally while maintaining them under tight compression and at the same time will maintain their magnetic centers in substantial coincidence along the winding leg 10 of the core. The core is supported by brackets 24 and levers 25 which distribute the weight of the core on the two coil stacks 11 and 12 as in the transformer shown in Fig. 2. The outer coil stack 12 is supported on fixed supports 23 mounted on the base 15. The inner coil stack 11 is supported by levers 26 which are pivoted at their inner ends to the fixed supports 23. The outer end of each lever is pivoted to the outer end of a secondary lever 27. Two rods 28 and 29 are connected by pivot joints from the inner end and center of each lever 27 to the inner and outer ends respectively of one of the levers 25. This construction keeps both coil stacks under constant compression, the levers 25 tilting to compensate for any inequality in shrinkage. A consideration of the arrangement of the levers 25, 26 and 27 and the rods 28 and 29 will also show that if either coil stack shrinks, the inner stack 11 will be moved or displaced automatically through a distance equal to one half the amount of this shrinkage so that relative displacement of the magnetic centers of the two stacks along the winding leg 10 of the core will be prevented. If both stacks shrink and their shrinkage is unequal, the automatic displacement of the inner stack will be equal to one half the difference between the shrinkage of the two stacks and their two magnetic centers will remain coincident in position on the winding leg of the core.

The construction shown in Fig. 4 is applicable where shrinkage will occur in one coil stack, the shrinkage of the other stack being small enough to be negligible. Here the outer coil stack 12 contains an appreciable amount of compressible insulation so that the stack will shrink in service but the inner stack 11 is of such construction that any shrinkage will be negligible. The outer stack 12 is mounted on fixed supporting means 23 carried by the base 15. The core is supported by brackets 24 and levers 25 which distribute the weight of the core on the two stacks of coils. The inner incompressible stack of coils 11 is mounted on the centers of levers 30, the inner end of each lever 30 being pivoted to the fixed supporting means 23 and its outer end being connected by a rod 31 to the outer end of one of the levers 25. It will be seen that when the outer stack 12 shrinks, the inner stack will be displaced through a distance substantially equal to one

half the shrinkage of the outer stack so that the magnetic centers of the two stacks will remain coincident in position along the winding leg 10 of the core. Fig. 7 is a plan view of the construction just described and shown in Fig. 4 and indicates how the levers 25 and 30 are provided with side extensions 32 between which the rods 31 are connected. Similar side extensions are of course provided in the construction shown in the other figures of the drawing.

The construction shown in Fig. 5 is similar to that shown in Fig. 2 except that the bottom supporting means for the two coil stacks consists of compensating levers 33 instead of fixed supporting means as in Fig. 2. Each lever 33 supports the two coil stacks 11 and 12 at its inner and outer ends respectively and is pivoted at its center to fixed supporting means 34 secured to the base 15. The outer end of each lever 33 is connected by a rod 35 to the inner end of one of the levers 25 at the upper ends of the two stacks of coils. Tilting of the levers 25 and 33 compensate for inequality of shrinkage in the two coil stacks 11 and 12 and it will be seen that the provision of compensating supporting levers at each end of the coil stacks, as shown in Fig. 5, will permit a greater inequality in the shrinkage of the stacks than will be permitted by such levers at one end only of the stacks as shown in Fig. 2. This is so because the angle through which the levers may be tilted is of course limited. Fig. 6 is a view in elevation of the construction shown in Fig. 5 and shows the side extensions 32 on the levers 25 and 33 between which the rods 35 are connected.

The invention provides means for maintaining two concentric stacks of coils of a transformer under constant tight compression, at the same time permitting one or both stacks to shrink while in service and keeping the magnetic centers of the two stacks exactly coincident or coincident within allowable limits along the winding leg of the core which they surround.

What I claim as new and desire to secure by Letters Patent of the United States is:

1. A transformer including two concentric cylindrical stacks of windings, and means responsive to shrinkage of one of said stacks of windings for moving the other of said stacks in the direction of said shrinkage. 115
2. A transformer including two concentric cylindrical stacks of windings, and means responsive to shrinkage of one of said stacks of windings for moving the other of said stacks through a distance less than the amount of said shrinkage and in the same 125 direction.
3. A transformer including two concentric cylindrical stacks of windings, and means responsive to shrinkage of the stacks of windings for moving one of said stacks to 130

4 prevent relative displacement of the magnetic centers of the two stacks.

4. A transformer including two concentric cylindrical stacks of windings, means including a lever for supporting one of said stacks of windings, and means connected to said lever and responsive to shrinkage of the

other of said stacks of windings for moving said first stack to prevent relative displacement of the magnetic centers of said stacks by shrinkage of said second stack.

In witness whereof, I have hereunto set my hand this 29th day of May, 1925.

FREDERICK F. BRAND.
